UNITED STATES PATENT OFFICE

90,517

DESIGN FOR A BRASSIÈRE

Ferdinand Tournier, Lyon, France

Application January 13, 1933. Serial No. 46,823

Term of patent 3½ years

To all whom it may concern:

Be it known that I, FERDINAND TOURNIER, a citizen of the Republic of France, residing at Lyon (Rhône) France, and whose post-office address is 4, Place des Carmélites, in said city, have invented a new, original, and ornamental Design for a Brassière, of which the following is a specification, reference being had to the accompanying drawing, forming part thereof.

Figure 1 of the drawing shows a front elevation of the brassière according to my new design and Figure 2 is a rear elevation of the back only of the brassière shown in Fig. 1.

I claim:—

The ornamental design for a brassière, as shown.

Signed at Lyon, France, this nineteenth day of May, 1933.

FERDINAND TOURNIER.
